(57) **CLAIM**

The ornamental design for an electrical component hanger as shown and described.

DESCRIPTION

FIG. 1 is a perspective view from a first side of the new design for an electrical component hanger in accordance with the present invention;

FIG. 2 is a perspective view from a second side of the electrical component hanger shown in FIG. 1;

FIG. 3 is a front elevation view from a front of the electrical component hanger shown in FIG. 1;

FIG. 4 is a rear elevation view from a rear of the electrical component hanger shown in FIG. 1;

FIG. 5 is a side elevation view of the first side of the electrical component hanger shown in FIG. 1;

FIG. 6 is a side elevation view of the second side of the electrical component hanger shown in FIG. 1;

FIG. 7 is a top plan view of the electrical component hanger shown in FIG. 1;

FIG. 8 is a bottom plan view of the electrical component hanger shown in FIG. 1;

FIG. 9 is a perspective view from a first side of another embodiment of the new design for an electrical component hanger in accordance with the present invention;

FIG. 10 is a perspective view from a second side of the electrical component hanger shown in FIG. 9;

FIG. 11 is a front elevation view from a front of the electrical component hanger shown in FIG. 9;

FIG. 12 is a rear elevation view from a rear of the electrical component hanger shown in FIG. 9;

FIG. 13 is a side elevation view of the first side of the electrical component hanger shown in FIG. 9;

FIG. 14 is a side elevation view of the second side of the electrical component hanger shown in FIG. 9;

(Continued)

FIG. 15 is a top plan view of the electrical component hanger shown in FIG. 9; and,
 FIG. 16 is a bottom plan view of the electrical component hanger shown in FIG. 9.
